UNITED STATES PATENT OFFICE.

ANDREW STENSRUD, OF OAKLAND, CALIFORNIA.

TWISTING TOOL.

Application filed February 19, 1923. Serial No. 620,030.

To all whom it may concern:

Be it known that I, ANDREW STENSRUD, a citizen of the United States, and a resident of Oakland, county of Alameda, State of California, have invented a new and useful Twisting Tool, of which the following is a specification.

The present invention relates to improvements in twisting tools generally, and has particular reference to a tool adapted to be used for the twisting of connecting rods used for gasoline engines. It is well understood in the art that it is essential for the perfect operation of a gasoline engine that the axes of the wrist pin and of the crank shaft be perfectly parallel, and this condition can be obtained only if the connecting rod is perfectly straight. It frequently happens, however, that while the connecting rod is in use twists develop in the same which have to be straightened out or compensated for by twists of an opposite character in order to secure parallelism of the two axes referred to. My tool is particularly designed to allow of the twisting or straightening out of the rod to be performed to a nicety, thereby insuring correct positions of the wrist pin relative to the crank shaft whereby best results may be obtained.

The preferred form of my invention is illustrated in the accompanying drawing in which Figure 1 shows a side view of my twisting tool, the position of the connecting rod being shown in dotted lines, Figure 2 an end view of the same, Figures 3 and 4 detail views explaining the working of my tool, Figure 5 a perspective detail view of a reducing member, and Figure 6 a view showing the relative position of the wrist pin to the crank shaft when the connecting rod is twisted. While I have shown only the preferred form of the invention, it should be understood that various changes or modifications may be made within the scope of the claims hereto attached without departing from the spirit of the invention. It should be particularly understood that while my tool is described in this specification with particular reference to a connecting rod, various other uses may be found for the same.

My tool consists principally of two gripping members (1) and (2), each of which is provided with an arm (3). The gripping members are formed very much like an ordinary hand wrench and comprise a disk pro-

vided with a recess (4) extending from the periphery of the disk to a line (6) well beyond the center. Of the two jaws (7) and (8) thus formed, one extends throughout the full dimension of the disk while the other (8) is shortened as shown in the drawing. The two members are arranged in parallel relation with a long jaw of one member opposing a short jaw of the other member, and vice versa, and are held in spaced relation by means of a spacing member (9) consisting of a sleeve interposed between the two members, and a spring (11) within the sleeve, the ends (12) of which extend through the two members and are bent into loops (13) on the outside of the same with cotter pins (14) passing through the loops and holding the spring in place.

The two arms (3) diverge from a center line passing through the center of the recess (4) in opposite direction in the manner shown in Figure 2, but converge along said central line as shown in Figure 1 so that a shaft (16) disposed transversely to the connecting rod to be worked on may pass through the two ends of the two arms. The perforations (17) provided in the ends of the two arms for this purpose are tapered in the manner shown in the drawing so as to allow the two arms to be moved relative to one another on the shaft. The latter is provided at one end with a collar (18) rotatable thereon, having projections (19) engaging registering recesses (21) in one of the arms, whereby the collar is held against rotation. The shaft terminates at this end in the head (22) of square or angular cross section which may be engaged by any suitable wrench for imparting rotary motion to the shaft. The other end of the shaft is engaged by a nut (24) disposed on the outside of the other arm, which nut is held against rotation by a projection (26) extending therefrom engaging a recess (27) in the arm, so that when the shaft (16) is turned clockwise the two arms of the two wrenches are drawn together. If the shaft is turned counter-clockwise the two arms are separated due to the tension of the spring (29) interposed between the same.

The manner of using my tool may be described as follows: If the connecting rod (31) is twisted in the manner indicated in Figures 3 and 4, which shows two cross sections through the same taken at distant

points adapted to be engaged by the two members of my device, the latter are engaged with the connecting rod at these two points in the manner illustrated in the said figures, that is the long jaw engages the side of the connecting rod that has to be twisted back into position, while the short jaw engages the lower edge of the other side. If now the shaft (16) is turned in a clockwise direction as viewed in Figure 1, a twisting effect will be obtained whereby the connecting rod is straightened out.

The importance of this operation may be understood from the illustration of Figure 6 in which the wrist pin (32) and the crank shaft (33) are shown in the position which they occupy when the connecting rod is twisted. In this position the two center lines (34) and (36) diverge and make a proper operation of the engine impossible. After my tool has been used on the connecting rod, the latter is returned to a position where it allows the axes of the wrist pin and the crank shaft to be parallel.

To allow my device to be used for connecting rods of different sizes, I provide a means for changing the size of the recess in the channel shaped filler (37) shown in

Figure 5 may be placed over the long jaw so as to decrease the width of the recess.

30

I claim:

1. Means for twisting a rod of the character described comprising two gripping members adapted to engage the rod at distant points, means for holding the same in spaced relation, arms extending from the gripping members formed to intersect a transverse line at distant points, yielding means tending to force the arms apart, a shaft extending through the arms coaxially with said line and threaded means engaging the shaft for forcing the arms together, whereby a twisting action is obtained.

2. In a twisting device of the character described, a wrench comprising a gripping element formed to engage an object on opposite sides for twisting action and a handle joining the said element at an angle to the plane of the object and at an angle to the plane of the gripping element in combination with a complementary wrench for producing twisting action and a spacing member between the two wrenches having yielding means associated therewith for forcing the two wrenches upon the spacing member.

ANDREW STENSRUD.
